E. B. DUNBAR

CURTAIN FRAME

Filed March 1, 1922

UNITED STATES PATENT OFFICE.

ETHEL B. DUNBAR, OF ELKHORN, WISCONSIN.

CURTAIN FRAME.

Application filed March 1, 1923. Serial No. 540,093.

To all whom it may concern:

Be it known that I, ETHEL B. DUNBAR, a citizen of the United States, residing in Elkhorn, in the county of Walworth, in the State of Wisconsin, have invented certain new and useful Improvements in Curtain Frames, of which the following is a specification, reference being had to the accompanying drawings, forming a part thereof.

The purpose of this invention is to provide a simple adjustable frame for supporting curtains or other fabrics to permit them to dry smoothly after a washing or other cleaning process. It consists of certain features and elements of construction and their combination hereinafter described and shown in the drawings as indicated by the claims.

In the drawings:

Figure 1 is a perspective view of a curtain frame embodying this invention.

Figure 2 is a perspective detail view of a modified cross bar for the frame.

Figure 3 is a detail section taken as indicated at line 3—3 on Figure 1.

The frame embodying this invention is designed to be adjustable for supporting curtains or other fabrics of various lengths and various widths. For this reason each of the uprights consists of two members, 1 and 2, which are suitably engaged with each other by means of U-shaped guide members, 3 and 4, and a clamping bolt, 5, which is set into the member, 1, and extends through a longitudinal slot, 6, in the member, 2; a washer, 7, and wing nut, 8, on the bolt, 5, serve for securing the parts, 1 and 2, at any position of longitudinal adjustment in the range of the slot, 6. The member, 1, terminates at its lower end in a foot piece or base, 9, and at a short distance above said base carries a cross-arm, 10, whose lower edge is formed with a plurality of notches, 11. The other part, 2, of the upright carries a similar cross-arm, 12, near its upper end, said cross-arm having notches, 13, formed in its upper edge. As shown in Figure 1, the curtain, A, is made with hems, A¹ and A², at its upper and lower edges respectively for engaging the supporting rods, B, by which the curtain is normally mounted at the window. After the washing process, these same rods, B, B, are inserted in the hems, A¹ and A², and the rods are then lodged in the notches, 11 and 13, as shown. The curtain, A, is spread to its full width upon the rods and the upright members, 2, are adjusted upwardly so as to separate the

cross arms, 10 and 12, by sufficient distance to put the curtain under a slight tension to insure that it shall dry smoothly.

As shown, the two uprights are laterally spaced apart by means of diagonal members, 15, pivotally attached by clamping bolts, 16, whose threaded ends project from one edge of each of the members, 1. The diagonals, 15, are formed with a plurality of holes, 15^a, longitudinally distributed to provide a range of lateral adjustment of the uprights for fitting the frames for curtains of different widths. When adjusted, the diagonals are quite firmly held in position by clamp nuts, 17, preferably of the wing type, but for additional rigidity a clamp, 18, may be added at the lapped intersection of the diagonals.

In the drawing, I have shown only a single curtain, A, mounted on the frame, purposely omitting additional curtains in order to show more clearly the details of the frame construction; it will be understood, however, that in most households there will be a number of curtains of similar dimensions, so that when the frame is once adjusted for a certain size, the plurality of notches, 11 and 13, will accommodate additional curtains of this size which will be spaced apart in parallel planes, so that they will dry independently of each other and will be stretched in the drying process to a definite and uniform size. Preferably the rods, B, should be of the common flat tubular type in which the tube is stiffened against deflection by mounting it with the longer axis of its cross section extending vertically; thus the upper and lower edges of the curtain are held practically straight during the drying. Any other form of rod which is relatively stiff may be employed, but since the vertical depth of such rods will usually be greater than their thickness horizontally, I prefer to make the notches, 11 and 13, of greater depth than width, so as to support such rods against twisting.

The design shown in Figure 1 lends itself readily to a wooden construction throughout, but in Figure 2 I have shown a design for a cast metal cross arm, 20, comprising a web portion, 21, and a peripheral flange, 22, which is interrupted at 23 and 24, to receive the upright member, 1 or 2, as the case may be. The flange, 22, may be cast to include notches, 25, corresponding to the notches, 11 and 13, of Figure 1. It will be seen that this cast fitting may be applied in the position shown to the upper ends of the upright members, 2,

and by merely inverting it, will be suitable for securement to the members, 1, at a distance above their bases. A single bolt, through the apertures, 26, and a screw 5 through the web at 27 will secure the fitting firmly to the upright member.

I claim:—

1. A frame comprising a pair of standards each formed with a base or foot and each supporting a lower cross arm and upper cross arm, each cross arm extending transversely of the common plane of the standards, and means connecting said standards in spaced relation with their respective 10 cross arms extending in substantially parallel planes, the upper surfaces of the upper cross arms and the lower surfaces of the lower cross arms being adapted to receive a plurality of rods extending in spaced relation to each other from the cross arms of one 15 standard to those of the other for engaging the upper and lower portions of a curtain or other fabric.
2. In the combination defined in claim 1, 20 said standards being each composed of two parts slidably engaged for vertical adjustment of one upon the other, one part being fixedly secured to the foot or base, and fixedly carrying the lower cross arm and the other part having the upper cross arm secured to it, whereby vertical adjustment of the latter part upon the former will vary the distance between the cross arms.
3. In the combination defined in claim 1, 25 the means which connects the standards in spaced relation comprising a pair of oppositely oblique diagonal members, each pivotally attached to the lower portion of one standard and to an upper point on the other standard, and clamping means engaging the diagonals at their intersection for securing said diagonals in any chosen 30 angular relation to the standards.
4. A frame comprising a pair of standards each formed with a base or foot, a plu- 45

rality of cross-arms carried by each of the standards and extending transversely of the plane defined by said standards, pairs of supporting rods engaging the cross-arms, each pair of rods defining a plane substantially parallel to that of the standards and means to maintain the standards and the supporting rods in any one of a plurality of predetermined spaced relations.

5. In the combination defined in claim 4, 50 said standards each comprising two parts one of which is fixed to the foot or base, the other being vertically slidable thereon, the means which maintains the standards in spaced relation comprising a pair of diagonal braces each of which is pivotally fixed at one end to the first mentioned parts of the standards and adjustably connected to the slidable parts of the standards whereby said slidable parts may be adjusted vertically independently of said diagonals.

6. In the combination defined in claim 4, 55 said standards each comprising two parts one of which is fixed to the foot or base, the other being vertically slidable thereon, the means which maintains the standards in spaced relation comprising a pair of diagonal braces each of which is pivotally fixed at one end of the first mentioned parts of the standards, the opposite ends of said diagonals being each provided with a plurality of longitudinally distributed apertures, and a pin carried by each of the slidable parts 60 of the standards designed to cooperate with the apertures of the diagonals.

7. In the combination defined in claim 1, 65 the base or foot portion of each standard comprising a flat transverse member extending substantially within the plane of the cross arms of said standard.

In testimony whereof, I have hereunto set my hand at Chicago, Illinois, this 24 day of February, 1922.

ETHEL B. DUNBAR.
